PRUNING TOOL HEAD

Albert M. Lindsay, Bremerton, Wash.

Application March 26, 1954, Serial No. 29,705

Term of patent 7 years

(Cl. D22—4)

To all whom it may concern:

Be it known that Albert M. Lindsay, a citizen of the United States, residing at Bremerton, Wash., has invented a new, original, and ornamental Design for a Pruning Tool Head, of which the following is a specification, reference being had to the accompanying drawing, forming a part thereof, in which:

Figure 1 is a perspective view of a pruning tool head, showing my new design;

Figure 2 is a top plan view;

Figure 3 is a side elevation; and

Figure 4 is a bottom plan view of the same.

I claim:

The ornamental design for a pruning tool head, as shown.
